UNITED STATES PATENT OFFICE.

JOSEPH A. LACLAIR, OF OWENDALE, MICHIGAN.

MILK-PAIL HOLDER.

1,266,327.

Specification of Letters Patent. Patented May 21, 1918.

Application filed August 14, 1917. Serial No. 186,187.

To all whom it may concern:

Be it known that I, JOSEPH ALFONSE LACLAIR, a citizen of the United States, residing at Owendale, in the county of Huron and State of Michigan, have invented certain new and useful Improvements in Milk-Pail Holders; and I do hereby declare the following to be a full, clear, and exact description of the invention, such as will enable others skilled in the art to which it appertains to make and use the same.

This invention relates to improvements in milk pail holders.

The object of this invention is to provide a holder capable of being removably secured to the pail at diametrically opposite points and so constructed as to be adjusted to compensate for pails of various thicknesses so that the holder may be readily and quickly adjusted and fitted to any size pail for supporting the same upon the knees of a person during the milking.

A further object of this invention is to provide a holder capable of being removably and adjustably clamped upon a pail, bucket or the like and so position the bucket as to be in the proper alignment for the milking.

A still further object of this invention is to provide a milk pail holder embodying a relatively stationary member and a pivoted movable member, each of the members being provided with depending lips through which are arranged screws adapted to permit the device to be adjustably and rigidly secured to the pail at diametrically opposite points and the movable member is adapted to be held in clamping engagement with the stationary member tightly binding the device upon the pail.

A further object of this invention is to provide a milk pail holder of this character, which will be simple, practical and comparatively inexpensive in construction, and one that can be manufactured and sold at a low cost.

With these and other objects in view, the invention consists in the novel combination and arrangement of parts hereinafter more fully described and set forth in the claims hereto appended.

In the drawing

Figure 1 is a front elevation partly broken away to illustrate the holder as applied to the pail and as made in accordance with this invention,

Fig. 2 is a top plan view of the holder,
Fig. 3 is a transverse sectional view of the holder,

Fig. 4 is a transverse sectional view taken 60 through the holder at the other end thereof, and

Fig. 5 is a longitudinal sectional view taken through the holder, partly broken away, to illustrate the device when in clamp- 65 ing engagement.

Like numerals of reference designate corresponding parts in all the figures of the drawing.

Referring to the drawing, the numeral 1 70 designates the handle of my holder and it comprises an arcuate body 2 having one end curved upwardly as at 3, the terminal of the upwardly curved portion bent downwardly and inclined inwardly as at 4 to provide a retaining or clamping member. The arcuate body 2 is provided adjacent its outer end with a pair of spaced longitudinally extending slots 5 in which is slidably arranged a locking ring 6. The upwardly curved portion 3 of the handle 1 is provided centrally of its side edges with spaced slits defining tongues 7 which are bent upwardly at right angles thereto. The clamping member 4 has screw threadedly arranged therein adjacent its lower end a thumb screw 8 which is arranged to extend transversely through the member 4 as illustrated in Fig. 5 of the drawing.

A lever 9 having an arcuate body has both 90 ends curved upwardly as at 10 and the inner upwardly curved end has its terminal bent downwardly at right angles thereto as at 11 and defines a clamping member coöperating with the clamping member 4 of the handle 95 to removably secure the handle to a milk pail or bucket as designated by the letter "A" in the drawings. The clamping member 11 has extending transversely therethrough an adjusting thumb screw 12 which 100 coöperates with the thumb screw 8 as a retaining member for the handle to firmly clamp the device upon a milk pail or bucket designated A. The downwardly depending clamping member 11 on the lever 9 is provided adjacent its point of juncture with spaced ears 13, which ears are formed integrally with the opposite side edges of the clamping member 11 and extend rearwardly as illustrated. A pin 14 is extended transversely through the ears 7 and 13, the handle and lever respectively to pivotally se- 110

cure the lever to and in the slots of the handle, which slots are defined by the ears 7.

It is to be understood that the handle and lever are constructed of any suitable metal suitable for the purpose and that the lever 9 is of a size less than the handle 1. The other end of the lever is adapted to be arranged under the locking ring 6 after the lever has been moved into engagement 10 with the outer side of the arcuate body 2 of the handle 1 as illustrated in Fig. 1 of the drawing.

It will be apparent by virtue of the screws 12 and 8 respectively, that the holder 15 may be adjusted to compensate for the walls of buckets or pails of various thicknesses and may be readily and quickly clamped thereto by simply arranging the lip of the handle on the interior of the bucket, forcing the lever downwardly, forcing the screw into contact with the exterior of the bucket or pail and arrange the outer end of the lever under the locking ring 6 and the device is ready for use. It will also be apparent that by virtue of the arcuate body 2, it will snugly and readily conform to the configuration of the knees, the pail may be positioned between the legs of the user, thus obviating the necessity of applying pressure to the exterior of the bucket by the knees and causing the person using the pail or bucket to become tired when milking.

While in the foregoing there has been shown and described the preferred embodiment of this invention, it is to be understood that such changes may be made in the combination and arrangement of parts as will fall within the spirit and scope of the appended claims.

40 What is claimed is:—

1. A milk pail holder comprising a handle, a clamping member at one end of the handle, an adjusting screw carried by the clamping member, a lever pivotally secured 45 to the handle, a clamping member carried by the lever and arranged in spaced parallel relation with the clamping member of the handle, and a locking means carried by the

handle and coöperating with the lever for holding the lever in engagement with the handle for urging the clamping members in the direction of each other.

2. A milk pail holder comprising a handle having an arcuate body, each end of the body curved upwardly, the terminal of the 55 upwardly curved body inclined downwardly and outwardly, a locking ring slidably mounted adjacent the outer end of the handle, spaced ears formed integrally with the handle at the upwardly curved portion, a 60 lever, ears formed integrally with the lever and located between the ears of the handle and pivotally secured thereto, a clamping member carried by the lever, adjusting screws arranged in the clamping members of 65 the handle and lever respectively, said clamping members of the handle and lever respectively adapted to be engaged on the wall of a milk pail at diametrically opposite points to facilitate the supporting of 70 the milk pail upon the knees of the user.

3. A milk pail holder comprising a handle formed of a single strip of material having an arcuate body, a depending clamping member, an adjusting screw arranged transversely through the clamping member, a 75 lever pivotally secured to the handle adjacent the clamping member, a clamping member carried by the lever arranged in spaced parallel relation with the clamping member 80 of the handle, an adjusting screw arranged transversely through the clamping member of the lever and coöperating with the adjusting screw of the handle to facilitate the removably securing of the same to a pail, 85 and a locking ring carried by the handle coöperating with the free end of the lever for normally holding the clamping members in engagement with the pail.

In testimony whereof I affix my signature 90 in presence of two witnesses.

JOSEPH A. LACLAIR.
